UNITED STATES PATENT OFFICE.

WALTER BROWN, OF CRESCO, IOWA.

GASOLENE-STOVE.

SPECIFICATION forming part of Letters Patent No. 608,388, dated August 2, 1898.

Application filed August 20, 1897. Serial No. 648,957. (No model.)

To all whom it may concern:

Be it known that I, WALTER BROWN, a citizen of the United States, residing at Cresco, in the county of Howard and State of Iowa, have invented certain new and useful Improvements in Gasolene-Stoves; and I do declare the following to be a full, clear, and exact description of the invention, such as will enable others skilled in the art to which it applies to make and use the same.

This invention relates to improvements in gasolene-stoves, and the novelty and many advantages will appear from the following description and claims when taken in connection with the annexed drawings, in which—

Figure 1 is a vertical longitudinal sectional view of my improved stove with a part of the support broken away. Fig. 2 is a cross-sectional view, taken in the plane indicated by the dotted line $\alpha\alpha$ of Fig. 1, with a part of the top plate broken away and the supports removed. Fig. 3 is a perspective sectional detail view illustrating the shelf, the vaporizing-chamber, and the gas and air flues; and Fig. 4 is a perspective view of the absorbent pad and its holder with parts broken.

Referring by letter to said drawings, A indicates the top plate of a stove, which may be that of an ordinary gasolene-stove, and while here shown as of the single-burner type it is obvious that any suitable number of burners might be employed. This top is supported on suitable legs a or other supports, as the stove-top and supporting means form no essential parts of my invention. Arranged at the rear or one side of the stove-top is a horizontal shelf B. This shelf may be composed of galvanized iron or other suitable material and may have a vertical flange b on one end wall and both sides, so as to receive and seat the vaporizing-chamber C and the absorbent arranged therein. This shelf may be suitably braced in position, such as by means of arms c , which may rest on the stove-top or be otherwise connected with the stove-support. Depending from the shelf B and at its forward end is a gas-feed tube D. This feed-tube has a horizontal branch d , which passes beneath the stove-top to a suitable distance and may be secured in position by a bracket e . The upper end of the vertical branch of the tube D may have the shelf B formed integral there-

with or rigidly fixed thereto and is of a peculiar construction, having its rear wall carried inwardly, as shown at f , so as to contract the throat thereof, and its opposite or forward wall is carried to a greater altitude than the rear inwardly-directed wall, as at h , and better shown in Fig. 3 of the drawings. This gas-feed tube, which is of an elongated rectangular form in cross-section, by preference is provided at a suitable altitude with lateral holes i , which are designed to furnish passages for air, and the tube is flared by carrying its side walls outwardly and upwardly, as shown at j and k . It will be observed that by extending the walls as shown at k a stop will be formed for the slideable pad-holder, as will be presently described.

The vertical branch of the gas-feed tube D is provided with a slideable collar E, which is designed to regulate and close the inward draft.

F indicates a burner which may be mainly of the ordinary construction. This burner is connected with the horizontal branch of the gas-feed by means of a drum g , which is placed over an aperture l in the horizontal branch d , and this drum passes through and is disconnected from the interior of a horizontal branch m of the hot-air tube, so that any gas which may pass from the feed-tube will not enter the hot-air tube.

G indicates the hot-air tube, which comprises a vertical branch and a horizontal branch, as shown. This tube is open at both ends and has passing through it the drum g . Depending from the burner-head and surrounding the upper part of the drum is a brass ring I, which extends into the horizontal branch of the hot-air tube. The drum is preferably composed of tin or other slow conductor of heat, while the ring I is composed of brass or material of a high conductive nature. By this means the ring will extract the heat from the burner and conduct it into the horizontal branch of the hot-air tube, when the air entering the lower end of said tube will absorb the heat and carry the same upwardly in the course indicated by the arrows.

The vaporizing-chamber C may be of a general rectangular form, as shown, so as to rest upon the shelf B. This chamber is open at its forward end to receive the absorbent-

holder J, which is designed to slide therein. The absorbent K may be composed of any suitable material which will absorb or take up the gasoline, and it is so fixed in the holder as to extend from side to side thereof and snugly against the front wall n, but leave a passage p above, a passage q, and another passage r below, so that the air entering the vaporizing-chamber will be directed over and around the entire surface of the absorbent. The chamber C is provided on its top at its forward end with a hinged hood or deflector L, which is designed to extend over the vertical plane of the hot-air tube, so as to deflect such hot air as may be received therefrom into the vaporizing-chamber, so that such air may become mingled with and absorb the gases and be carried back and down through the course indicated by the arrows 20 and to the burner to be consumed.

The absorbent-holder J is provided externally on its front wall with a suitable handle, whereby it may be carried to a suitable can to be saturated with gasoline, and below this handle I provide a transverse strip s, which is designed to overlap the upper edge h of the gas-feed tube. By the employment of this strip it will be seen that the throat of the gas-feed tube may be regulated so as to govern 25 the passage of gas from the vaporizing-chamber to the burner. It will be seen that by sliding the absorbent-holder inwardly from the position shown in Fig. 1 the passage may be closed to any desired extent. This is very 30 desirable in shutting out the flame or burner, for the reason that the passage will not be entirely closed when the flame is shut out. If the throat of the gas tube should be entirely closed by sliding the absorbent-holder inwardly, the flame would be shut out before the gas in said tube would have time to descend 35 and be consumed, while by leaving a slight opening there will be sufficient downdraft to entirely consume all of the gas in the feed-40 tube before cutting off the flame.

By the employment of the collar E it will be seen that more or less air may be admitted into the gasoline-tube, and when there is sufficient air admitted through the hot-air tube the collar may be moved to entirely close the aperture in the gas-tube. The deflector L may have a curved top, so as to serve more effectively in directing the hot-air currents.

With a stove constructed as described the 55 danger of spilling or leakage of the gasoline is reduced to a minimum and there is no danger of explosion.

While I have shown and described my preferred construction, yet I do not wish to be understood as limiting myself to the details which I have set up, as it is obvious that many of the parts can be altered without departing from the spirit of my invention. The tubes may in some cases be made round, the slide-60 able collar may be altered so as to use a draft-regulator of other type, and the absorbent may be of any previous material.

Having thus described my invention, what I claim is—

1. In a gas or vapor stove, the combination 70 of a vaporizing-chamber, a burner, a gas-feed tube connecting the vaporizing-chamber and the burner, and a slidable absorbent-holder arranged in the vaporizing-chamber and controlling communication between the said 75 chamber and the gas-feed tube and consequently the quantity of gas supplied to the burner, substantially as specified.

2. The combination with a suitable burner and a vaporizing-chamber; of a gas-feed tube 80 having the upper end of its rear wall directed inwardly and its front and side walls carried above the rear wall, and a slidable absorbent-holder adapted to move over the mouth of the feed-tube so as to regulate the feed, substan- 85 tially as specified.

3. In a gas or vapor stove, the combination 90 of a vaporizing-chamber, a burner, a gas-feed tube connecting the vaporizing-chamber and the burner, and a slidable absorbent-holder arranged in the vaporizing-chamber and controlling communication between the said 95 chamber and the gas-feed tube and consequently the quantity of gas supplied to the burner; the said absorbent-holder being provided with a portion adapted to close the feed-tube to the atmosphere when communication between the said tube and the vaporizing-chamber is partially closed and also adapted, when the feed-tube is entirely closed 100 to the vaporizing-chamber, to assume such a position as to establish communication between the feed-tube and the atmosphere, substantially as specified.

4. The combination with a suitable burner; 105 of a vaporizing-chamber open to the atmosphere, a gas-feed tube, a hot-air tube open at both ends to the atmosphere, and a hood adapted to direct the hot-air currents into the vaporizing-chamber, substantially as specified. 110

5. In a gas or vapor stove, the combination 115 of a vaporizing-chamber open at one end to the atmosphere and provided above such open end with a deflector, a burner, a gas-feed tube connecting the vaporizing-chamber and the burner, an air-tube arranged to receive the heat of radiation from the burner and discharge the same against the deflector, and a removable, slidable absorbent-holder arranged in the vaporizing-chamber and controlling communication between the said 120 chamber and the gas-feed tube; said absorbent-holder being provided with a portion adapted to close the feed-tube to the atmosphere when communication between the said tube and the vaporizing-chamber is partially closed and also adapted, when the feed-tube is entirely closed to the vaporizing-chamber, to assume such a position as to establish communication between the feed-tube and the 125 atmosphere, substantially as specified. 130

6. In a gas-stove, the combination with the gas-feed tube; of the vaporizing-chamber, the slidable absorbent-holder having the strip

on its front wall sliding in contact with the upper end of the gas-feed tube so as to regulate the opening between the gas-feed tube and the vaporizing-chamber, and a suitable means for admitting air to said chamber, substantially as specified.

7. In a gas-stove, the combination with a burner; of the gas-feed tube having its vertical branch perforated and a slidable collar thereon, a drum leading from said tube to the burner, the vaporizing-chamber having the hinged door or deflector and connected with the gas-feed tube, the absorbent-holder arranged in said chamber so as to al-

low a passage around the absorbent, the hot-air tube having its vertical branch adapted to discharge against the deflector or hood of the vaporizing-chamber, and the ring extending from the head of the burner into the horizontal branch of the air-tube so as to conduct the heat therein, substantially as specified. 15 20

In testimony whereof I affix my signature in presence of two witnesses.

WALTER BROWN.
